DEFENSIVE PUBLICATION

UNITED STATES PATENT AND TRADEMARK OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent and Trademark Office makes no assertion as to the novelty of the disclosed subject matter.

U.S. Cl. 444—1

8 Sheets Drawings. 36 Pages of Specification

An automated circuit design system and process are provided including a technique for introducing redundancy of circuit element groups during the allocation of the circuit element groups to modules. The redundancy technique, which is embodied as a computer algorithm, functions when the allocation of redundant element such as a circuit element group is made to a container module such as a circuit chip, during a discrete step allocation procedure which is designed to produce a mapping of a set of connected circuit elements. A minimum condition for obtaining a successful mapping is that each element can be allocated to at least one module. The operation of the process is made redundant to reduce the number of elements by one, namely the allocated element. The consequence of the operation is that the connected elements said to be fed by the redundant element (referred to as sink elements) are each combined by union with the redundant element. Other concomitant results of the operation are that the connections previously required between the redundant element and its sink elements will not be needed should any of the sink elements be allocated to different modules, and each sink element has acquired the attributes of the redundant element.

Sheet 5 of 8

CREATE A CANDIDATE VERTEX LIST CONSISTING OF
ALL ALLOCABLE VERTICES WHICH SHARE A NET
WITH THE VERTICES THUS FAR ALLOCATED.

SELECT j' FOR SMALLEST $R_{j'}$ -TIES BROKEN ARBITRARILY.

SELECT i' FOR SMALLEST F_{ij} FOR THIS j -TIES BROKEN
ARBITRARILY.

ALLOCATE VERTEX j' TO MODULE i'

ALTER PIN AND AREA CAPACITIES ON MODULE
AND REMOVE VERTEX FROM CANDIDATE LIST.

IS THIS A REDUNDANT PASS
AND IS VERTEX REDUNDABLE ?

YES

NO

DOES VERTEX MERIT BEING
MADE REDUNDANT ?

YES

NO

ALTER VERTEX GRAPH AND CONTROL
VARIABLES TO MAKE VERTEX j REDUNDANT

DECREMENT BY ONE THE PINS REQUIRED
FOR VERTEX j ALLOCATED TO MODULE i

ARE ALL ALLOCABLE VERTICES ALLOCATED ?

YES

NO

ALLOCATION ATTEMPT IS SUCCESSFUL;
SUPPLY MAPPING RESULTS TO USER

COMPUTE THE AREA A_{ij} NEEDED IF CANDIDATE
VERTEX j WOULD BE ADDED TO MODULE i
OVER ALL i AND j

COMPUTE THE PINS P_{ij} NEEDED IF CANDIDATE
VERTEX j WOULD BE ADDED TO MODULE i
OVER ALL i AND j .

SELECT THE NEXT VERTEX j MODULE i PAIR
